UNITED STATES PATENT OFFICE.

EMILE HENRY, OF PARIS, FRANCE, ASSIGNOR TO SOCIETE ANONYME DES HAUTS-FOURNEAUX ET FONDERIES DE PONT-A-MOUSSON, OF MEURTHE ET MOSELLE, FRANCE.

PAVEMENT.

1,347,855.

Specification of Letters Patent. Patented July 27, 1920.

Application filed April 11, 1919. Serial No. 289,239.

To all whom it may concern:

Be it known that I, EMILE HENRY, citizen of the Republic of France, residing at 5 Rue Jules Lefebvre, Paris, in the Republic of France, have invented new and useful Improvements in Pavements, of which the following is a specification.

This invention relates to an improved construction of pavement for roadways, side-walks, quays, etc., in which cast iron blocks having a special shape are laid upon a floor or foundation made of coarse concrete or other material, said cast iron blocks being more or less distant from each other without 10 contacting or abutting one another and being embedded in a layer of cement or concrete coming flush with the upper surface of the blocks. The said blocks, which form the frame or skeleton of the roadway, have 15 a reduced weight in proportion to a comparatively important wearing thickness, the uncovered cast iron surfaces are small and preferably located in a direction at right angles to the direction of the traffic on the 20 area to be paved.

In the annexed drawing, given by way of example, Figure 1 is a plan view showing a portion of a roadway provided with a pavement constructed in accordance with the invention.

Fig. 2 is a vertical section along the line X—X in Fig. 1.

Fig. 3 is a plan view similar to Fig. 1 showing a modification in the shape of the 30 blocks for the purpose of reducing the portions of the blocks located in a direction parallel to the axis of the road and increasing the portions at right angles thereto.

The cast iron blocks *a* which may have the 40 shape illustrated on the drawing, are laid down in suitable relative positions upon a foundation *d* of coarse concrete or any other material and embedded in a layer *e* of cement or thin concrete which is flush with the 45 upper face or edge of the blocks. In Fig. 1, all the blocks *a* have the same shape. In Fig. 2, two kinds of blocks *b* and *c* are shown for the purpose above mentioned.

Among the advantages of the improved

pavement, the following may be cited: Owing to the shape of the blocks they may easily be spread apart farther or closer at will so that different parts of the surfaces to be paved may be more or less strongly armored according to the strain to which 50 they are subjected (middle part or sides of a road for instance).

The shape illustrated corresponds also to a reduced weight (varying from 0k900 to 1K100 per block), so that the metal necessary for paving a square meter for instance is about 25 kilograms at the maximum, which weight is low in proportion with other types already known and corresponds to an advantageous cost price. The wearing thickness of the blocks is comparatively important (about 40 mm.). The blocks have only small uncovered cast iron surfaces, which lie mostly in a direction at right angles to that of the road. This acts efficiently to prevent slipping.

The roadway constructed as above described has a very long life and requires practically no upkeep, it stands perfectly neat even after snowfalls and frost.

The difficulty arising from the difference in hardness between cast iron and concrete may be removed either by using a concrete comprising hard materials: grit-stone, quartz, small trapp, etc., or by adding porphyry to the cement, the mixture giving a product which is remarkably hard and similar to carborundum.

Having now described my invention what I claim as new and desire to secure by Letters Patent is:—

1. A pavement comprising in combination: a foundation, a concrete surface layer on said foundation, and cast iron blocks distant from each other in all of their parts, embedded in said surface layer and extending entirely throughout the same, each block being composed of a thin vertical wall forming a closed figure of an approximately rectangular shape and outer radial arms, the arms on each block extending between the arms of the adjacent blocks.
2. A pavement comprising in combina-

tion: a foundation, a surface layer composed of cement and porphyry on said foundation and cast iron blocks distant from each other in all of their parts; embedded in said surface layer and extending entirely throughout the same, each block being composed of a thin vertical wall forming a closed figure

of an approximately rectangular shape and outer radial arms, the arms on each block extending between the arms of the adjacent 10 blocks.

In testimony whereof I have signed my name to this specification.

EMILE HENRY.
